COAXIAL LINE TO WAVE GUIDE MATCHING SECTION

Lloyd P. Hunter, Oak Ridge, Tenn., assignor to
Westinghouse Electric Corporation, East Pittsburgh, Pa., a corporation of Pennsylvania

Application December 27, 1947, Serial No. 794,148

5 Claims. (Cl. 178—44)

1

My invention relates to junctions of coaxial cables to wave guides for transmitting ultra-high-frequency electromagnetic energy, and in particular relates to a novel disposition of the coaxial cable relative to the wave guide to which connection is made.

It has been conventional in the prior art to effect a junction between a coaxial cable carrying ultra-high-frequency electromagnetic energy and a wave guide through which the energy is to flow by arranging the axis of the coaxial cable normal to the central axis of the wave guide at the junction, the end of the wave guide near the junction being closed by a conducting wall, and the central core of the wave guide usually being positioned in the neighborhood of a quarter wave length distant from this partition. The axis of the coaxial cable is conventionally normal to the surface of the wave guide at its point of entry, where the wave guide is a rectangular cross section, the coaxial cable passes through the middle of one wall of the guide.

I have found that while, in such conventional junctions, the characteristic impedance of the wave guide may be sufficiently well matched to that of the coaxial cable by methods well known in the art, the arrangement is usually quite frequency sensitive so that if it is desired to transmit a fairly broad band of frequencies it is necessary to resort to alterations of the shape of the junction, such as the provision of tuning devices which make the arrangement complicated and difficult to manufacture. It is also frequently awkward from the standpoint of space limitations to be compelled to have the axis of the coaxial cable normal to the axis of the wave guide.

One object of my invention is accordingly to provide a novel way of connecting a coaxial cable to a wave guide which shall avoid the awkward space limitation imposed by junctions of the prior art for such elements.

Another object of my invention is to provide a junction between a coaxial cable and a wave guide which is less sensitive to frequency variations of the electromagnetic energy being transmitted through them than were junctions of the prior art.

Still another object of my invention is to provide a new form of junction between a coaxial cable and a wave guide which shall have a relatively broad frequency acceptance while at the same time preserving a voltage standing wave ratio at least as good as those of junctions conventional in the prior art for such elements.

Still another object of my invention is to pro-

2

vide a novel type of junction between a coaxial cable and a wave guide which shall be of simple form and easy manufacture while at the same time preserving a transmission efficiency equal to junctions between such elements of the prior art type.

Still another object of my invention is to provide a form of junction between a coaxial cable and a wave guide which shall be relatively insensitive to frequency variations while at the same time it is easy to manufacture and free from the necessity for providing complicated adjustable tuning devices.

Other objects of my invention will become apparent upon reading the following description, taken in connection with the drawings, in which the single figure shows an embodiment of my invention suitable for joining a coaxial cable of circular section with a wave guide of rectangular section.

Referring in detail to the drawings, a wave guide 1 which may have the rectangular cross section which is well known in the wave guide art, comprises parallel conducting side walls and 25 likewise a parallel conducting top and bottom wall. The width of this guide may, for example, be twice the height, although it is to be understood that my invention is not limited to employment with dimensions of this particular ratio. 30 While such a wave guide is capable of transmitting electromagnetic energy in a number of different modes of vibration which are well known to those skilled in the art, I will mention as an example of these a mode of vibration in which 35 the electric vectors extend vertically between the top and bottom walls and vary sinusoidally in density distribution, both parallel to the axis of the guide and in the direction transverse to the guide. Such a mode of vibration is sometimes referred to as a $TE_{0,1}$ type of wave transmission.

The wave guide 1 has a conducting end wall 2 perpendicular to its axis which is provided with a central circular opening of the same size as the internal diameter of the sheath 3 of a concentric line supplying energy to the guide. The sheath 3 makes a tight abutment with the end wall 2. The central core 4 of the concentric line extends in substantial coincidence with the central axis of the guide 1 into the interior of the latter for some distance and then turns at right angles in the plane of the electric vector to make contact with the face of the guide. I have found that a good match between the impedance of the concentric line and the guide results if the distance between the above mentioned point of

attachment of the core to the guide wall from the end wall 2 is about one-half of the wave length of the electromagnetic energy being transmitted. I have likewise found it desirable for many purposes to provide a diaphragm 5 extending part way across the guide 1 at a short distance beyond the end of the core 4 of the coaxial line, this diaphragm 5 being one form of inductive diaphragm which may be proportioned to match out any small irregularities and reflections introduced into the transmitted waves by the junction of the coaxial line and the wave guide. Other types of inductive diaphragm may be employed for this purpose where desirable.

To give a specific example, I once used a rectangular wave guide having a width of 2.84" and a height of 1.34", inside dimensions, and made of copper which was connected as I have described above to a coaxial line having a sheath of brass which is $1\frac{17}{32}$ inches in inside diameter and a core of brass of $\frac{5}{8}$ of an inch diameter. When transmitting in the above mentioned TE_{0,1} mode of vibration electromagnetic waves having an open-air wave length of 10.6 cm., the system was operated over a range of frequency and I found that the standing wave ratio in the wave guide remained between 1.1 and 1.0 for a 5% change in frequency, while the standing wave ratio in the coaxial line remained within the limits 1.03 and 1.00. The core of the coaxial line in these tests projected 3.25 inches into the wave guide from the end wall 2, and the diaphragm 5, which was 8.76 inches from the end of the guide 1, extended from top to bottom of the guide adjacent one wall and had a width of 0.437 of an inch.

I claim as my invention:

1. In an electromagnetic wave transmitting system, a rectangular wave guide having an end wall and a coaxial transmission line joining said wave guide with its central core parallel to the central axis of the wave guide at their junction, one end of its sheath being in abutment with said end wall of said guide, and its central core extending into said guide for a distance about equal to one-half wave length of the waves traversing said coaxial line and being connected with a side wall of said wave guide whereby the impedance of said wave guide is substantially matched to the impedance of said coaxial transmission line.

2. In combination, a rectangular wave guide having an end wall and a coaxial transmission line joining said wave guide with its central core parallel to the central axis of the wave guide at their junction, one end of its sheath being in abutment with said end wall of said guide, and its central core extending into said guide for a distance about equal to one-half wave length corresponding to a mode of wave vibration which said guide is capable of transmitting, and making

contact with a side wall of said guide whereby the impedance of said wave guide is substantially matched to the impedance of said coaxial transmission line.

5. 3. In combination, a rectangular wave guide having an end wall and a coaxial transmission line joining said wave guide with its central core parallel to the central axis of the wave guide at their junction, one end of its sheath being in abutment with said end wall of said guide, and its central core extending into said guide for a distance about equal to one-half wave length corresponding to the TE_{0,1} mode of transmission of said guide and making junction with a side wall of said guide whereby the impedance of said wave guide is substantially matched to the impedance of said coaxial transmission line.
10. 4. In combination, a rectangular wave guide having an end wall and a coaxial transmission line joining said wave guide with its central core parallel to the central axis of the wave guide at their junction, one end of its sheath being in abutment with said end wall of said guide, and its central core extending into said guide for a distance about equal to one-half wave length corresponding to the TE_{0,1} mode of transmission of said wave guide and making junction with a side wall of said wave guide whereby the impedance of said wave guide is substantially matched to the impedance of said coaxial transmission line.
15. 5. In combination with a rectangular wave guide having an end wall and a coaxial transmission line joining said wave guide with its central core parallel to the central axis of the wave guide at their junction, one end of its sheath being in abutment with said end wall of said guide, and its central core extending into said guide for a distance about equal to one-half wave length corresponding to the TE_{0,1} mode of transmission of said wave guide and making junction with a side wall of said wave guide whereby the impedance of said wave guide is substantially matched to the impedance of said coaxial transmission line, and an inductive diaphragm in said wave guide beyond its junction with said core.

20. 35. 5. In combination with a rectangular wave guide having a transverse end wall, a coaxial line having one end of its sheath joined to said end wall of said guide, and having its core extending through said end wall parallel to the central axis of said wave guide and extending beyond said end wall for a distance about equal to a half-wave length of the TE_{0,1} mode of transmission of waves through said guide and turning parallel to the electric vector of said waves and making juncture with a wall of said guide whereby the impedance of said wave guide is substantially matched to the impedance of said coaxial transmission line, and an inductive diaphragm means in said wave guide beyond the said juncture.
25. 30. 45. 50. 5. In combination with a rectangular wave guide having a transverse end wall, a coaxial line having one end of its sheath joined to said end wall of said guide, and having its core extending through said end wall parallel to the central axis of said wave guide and extending beyond said end wall for a distance about equal to a half-wave length of the TE_{0,1} mode of transmission of waves through said guide and turning parallel to the electric vector of said waves and making juncture with a wall of said guide whereby the impedance of said wave guide is substantially matched to the impedance of said coaxial transmission line, and an inductive diaphragm means in said wave guide beyond the said juncture.
